UNITED STATES PATENT OFFICE

ELIAS W. CRAIG, OF WELLSVILLE, KANSAS

HOE

Application filed May 4, 1929. Serial No. 360,510.

My invention relates to improvements in hoes.

One of the objects of my invention is to provide a novel hoe which is particularly well adapted for weed and brush cutting as well as for cultivating the ground.

A further object of my invention is the provision of a novel means for attaching the handle to the blade by which the handle can be adjusted to different positions with respect to the blade, for the adaptation of the hoe to different uses.

A further object of my invention is the provision of a novel hoe blade which is approximately triangular in form and the three edges of which are cutting edges and adapted for different uses.

Still another object of my invention is to provide a novel hoe of the kind described, which is simple in structure, cheap to make, strong and durable and not likely to get out of order, and which is easy to use.

The novel features of my invention are hereinafter fully described and claimed.

In the accompanying drawings, which illustrate the preferred embodiment of my invention,

Fig. 1 is a top view of my improved hoe, part of the handle being broken away.

Fig. 2 is a side elevation of the same, showing the handle in solid lines in one operative position, and showing in dotted lines the handle in another operative position.

Fig. 3 is a side elevation, partly broken away, showing the relative position of the hoe to the ground, when the handle is disposed as shown.

Similar reference characters designate similar parts in the different views.

1 designates an approximately triangular flat thin hoe blade having its three edges cutting edges, the edge 2 being concavely arcuate, and the edges 3 and 4 having their portions, which are adjacent to their meet-

ing point, straight and at an angle to each other, as designated by 5, the remaining portions of said edges being convexly arcuate, Fig. 1.

6 designates the hoe handle, which has two parallel arms 7 disposed respectively at opposite sides of a plate 8, which is perpendicular to the blade 1, and which has two arms 9 and 10 projecting laterally from one side of the body of the plate and a third arm 11 extending laterally at the other side of the plate 8, said arms 9, 10 and 11 being fastened by rivets to the upper side of the blade 1.

The plate 8 is provided with a plurality of transverse holes 12 arranged in an arcuate row and being each adapted to receive therethrough a fastening device, such as a bolt 13 which is removably mounted in a hole extending through the arms 7 of the handle. The bolt 13 has mounted on it a thumb nut 14, which is adapted to bear against the arm 7 adjacent thereto.

A pivot member comprising a bolt 15 extends through the arms 7 adjacent to their outer ends, and through a hole through the plate 8 at the point of intersection of the radii which respectively extend through the holes 12. The bolt 15 has on it a nut 16 which bears against the adjacent arm 7 of the handle.

When it is desired to use the hoe for cutting weeds or brush, or for ordinary hoeing, the bolt 13 and handle 6 are adjusted on the plate 8, by swinging the handle on the bolt 15, to the position shown in solid lines in Figs. 1 and 2.

The plate 8 and the handle 6 are disposed in a plane perpendicular to the blade 1 and which intersects the meeting point of the portions 5 with each other, and which plane intersects the cutting edge 2 of the blade at a point farther from one end of the edge 2 than the other end thereof. The said farther end is also farther from a trans-

verse plane, intersecting the first named plane at right angles and disposed at the intersection of said first named plane with said edge 2, than the other end of said edge 2.

- 15 3. By means of this construction, the part of the cutting edge 2 at the right of the handle 6, as viewed in Fig. 1, is not as long as the portion of said edge at the left of the handle, so that the right side should be used when cutting thick weeds or brush, as a greater leverage is afforded. The other side of the blade may be used for deeper cutting or cutting light weeds.

10 Due to the concave arcuate edge, disposed as described, weeds and brush will be cut easily with a drawing and sliding stroke, after the manner of cutting with a curved sickle or scythe, when the handle is disposed as in Fig. 1, and as shown in solid lines in Fig. 2.

15 The hoe may be used with the blade 1 horizontal and drawn or pushed, or the blade may be tilted laterally as for disking the ground.

- 20 23. When it is desired to work the hoe around between plants which are close together, the handle may be adjusted to the position shown in Fig. 3 and in dotted lines in Fig. 2. The straight portions 5 of the edges 3 and 4 are then used for the hoeing operation.

25 The hoe may also be used so as to cut weeds above or below the ground by disposing the blade 1 horizontally and pushing and 30 pulling the handle so as to reciprocate the blade.

- 35 40. I do not limit my invention to the structure shown and described, as modifications, within the scope of the appended claims, may be made without departing from the spirit of my invention.

45 What I claim is:—

50 1. A hoe having an approximately triangular blade having its three edges cutting edges, one edge being concavely arcuate, the two other edges having straight forward portions meeting at their outer ends to form a point and rearward portions convexly arcuate, a handle, and means fastening said handle to said blade with the handle disposed in a plane perpendicular to the blade and intersecting said point of meeting and said concavely arcuate edge.

55 2. A hoe having an approximately triangular blade having its three edges cutting edges, one edge being concavely arcuate, the two other edges having straight portions meeting and forming a projecting point opposite to said concavely arcuate edge, a handle, and means fastening said handle to said blade with the handle disposed in a plane perpendicular to the blade and intersecting said point of meeting and said concavely arcuate edge, said plane of said handle intersecting said concavely arcuate edge of said

blade at a point farther from one end than from the other end of said concavely arcuate edge, said first named end being also farther than said other end from a transverse plane which intersects perpendicularly the first named plane at the intersection of the latter with said concavely arcuate edge.

70 In testimony whereof I have signed my name to this specification.
